US0D1044452S

(12) **United States Design Patent** (10) **Patent No.:** **US D1,044,452 S**
(45) **Date of Patent:** **** Oct. 1, 2024**

(54) **PART OF CASE OF POWER TOOL**

(71) Applicant: **MOBILETRON ELECTRONICS CO., LTD.**, Taichung (TW)

(72) Inventors: **Cheng-I Teng**, Taichung (TW);
Tung-Chin Kuo, Taichung (TW)

(73) Assignee: **MOBILETRON ELECTRONICS CO., LTD.**, Taichung (TW)

(**) Term: **15 Years**

(21) Appl. No.: **29/881,866**

(22) Filed: **Jan. 6, 2023**

(51) LOC (14) Cl. **08-05**

(52) U.S. Cl.

USPC **D8/69**

(57) **CLAIM**

The ornamental design for a part of case of power tool, as shown and described.

DESCRIPTION

FIG. 1 is a top, front and right side perspective view of a part of case of power tool embodying our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a bottom, front and left side perspective view thereof; and, FIG. 9 is a perspective view thereof, in which the article is shown with an exemplary power tool in a state of use. The broken lines in FIGS. 1-8 illustrate portions of the part of case power tool that form no part of the claimed design. The broken line showing the power tool in FIG. 9 is provided for the purpose of illustrating environmental structure and also do not form part of the claimed design.

1 Claim, 9 Drawing Sheets
